(57) **CLAIM**

The ornamental design for display panel with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first image in a sequence showing a display panel with animated graphical user interface;

FIG. 2 is a front view of a second image thereof;

FIG. 3 is a front view of a third image thereof;

FIG. 4 is another front view of FIG. 1 shown enlarged for clarity of illustration;

FIG. 5 is another front view of FIG. 2 shown enlarged for clarity of illustration; and,

FIG. 6 is another front view of FIG. 3 shown enlarged for clarity of illustration.

The appearance of the transitional image sequentially transitions between the images shown in FIGS. 1 through 3. The process or period in which one image transitions to another image forms no part of the claimed design.

The evenly-spaced broken lines showing an electronic device in FIGS. 1-3 illustrate environmental structure; the remaining evenly-spaced broken lines in the figures showing the display panel and portions of the graphical user interface illustrate portions of the article; the unevenly-spaced broken lines in the figures show the boundaries of the claimed design; all broken lines form no part of the claimed design.
